UNITED STATES PATENT OFFICE.

WILLIAM O. MUNDY, OF ST. LOUIS, MISSOURI, ASSIGNOR TO GENERAL ELECTRIC COMPANY, A CORPORATION OF NEW YORK.

MOTOR-CONTROL SYSTEM.

SPECIFICATION forming part of Letters Patent No. 795,000, dated July 18, 1905.

Application filed February 20, 1903. Serial No. 144,195.

To all whom it may concern:

Be it known that I, WILLIAM O. MUNDY, a citizen of the United States, residing at St. Louis, in the State of Missouri, have invented 5 certain new and useful Improvements in Motor-Control Systems, of which the following is a specification.

My invention relates to systems of motor control employing controllers comprising a 10 plurality of separately-actuated contacts, and relates more particularly to the construction and arrangement of the electromagnetically-actuated contacts or switches used in such systems.

15 In train-control systems such as that shown and described in the patent to C. L. Perry, No. 687,060, granted November 19, 1901, a motor-controller comprising a plurality of separately-actuated contacts is employed, each of 20 said contacts being operated electromagnetically and controlled from a master-controller located in any desired part of the car or train. In the system shown in said patent a number of the electromagnetically-actuated switches 25 or contactors are used for the purpose of varying the resistance in the motor-circuit, while others are used for connecting the motors in series or in parallel relationship. In the said patent the contactors are so arranged that the 30 conductor leading from one of the contacts of each switch used for varying the resistance in the motor-circuit and from the switch or switches used for connecting the motors to the source of power is connected for convenience 35 to a common conductor which forms part of the motor-circuit.

The object of my invention is to so construct and arrange the contactors of such a motor-control system as that shown in said patent to 40 Perry that the cost of manufacture and the space occupied by the said contactors when in their operative position on the car are materially reduced. This is accomplished by grouping together on a single frame of conducting material the contactors which are to have their contacts electrically connected to the common conductor, above referred to, and by allowing the frame itself to form said common conductor. This construction obviates

the necessity for using a great number of terminals, connections, and supporting parts and presents a more compact structure than has been used heretofore.

A further object of my invention is to produce a more efficient contactor and blow-out 55 chute; and to this end my invention consists of improvements in the construction of the blow-out chute and the arrangement of the same relative to the contactor and its actuating mechanism. This construction and arrangement will be hereinafter more clearly described, and the novel features will be particularly pointed out in the appended claims.

In the accompanying drawings, which illustrate one embodiment of my invention, Figure 65 1 represents diagrammatically a train-control system in which the contactors are arranged in accordance with my invention. Fig. 2 is a perspective view of two of said contactors mounted on a single frame of conducting material, showing clearly the relative arrangement of the blow-out chute and switch-actuating mechanism. Fig. 3 is a sectional elevation of one of said contactors, and Fig. 4 is a diagrammatic representation of the electrical 70 connections of one of said contactors.

Referring now to Fig. 1, M M represent the master-controllers of a train-control system in which the separately-actuated contacts T' T' R' R' R' R' R' R' S P P form the 80 controller for the motors M' M'. The said contactors are adapted to connect the motors to the trolley or collector shoe T and also to insert the required amount of resistance in the motor-circuit during acceleration. The resistances controlled by the resistance-contactors are represented by r' to r⁶, inclusive. The motor-circuits are represented by heavy lines, while the control-circuits, in which the actuating-coils of the contactors are located, are 90 represented by light lines. The resistances which are connected in the control-circuits are represented by r^a, r^b, r^c, r^d. The conductors of the control-circuits are connected with the proper contact-fingers in the master-controllers M M and are bound together in the form of a cable C, which runs throughout the train, the terminals C' being provided for the pur- 95

pose of connecting the cable of one car to the cable of the next adjacent car. A more detailed description of the connections of this system may be obtained from the patent above referred to. In the said patent to Perry the contactors are so arranged that those which control the motor-circuit resistances—viz., T' T' R' to R', inclusive, and R' R'—have one contact connected to a common conductor. Also one of the contacts of one of the contactors P is connected to the same conductor to which one of the contacts of S is connected. In the arrangement formerly employed it was necessary to use connectors and binding-posts for connecting each separate contactor to the said common conductor; but in my improved arrangement I have greatly reduced the number of connectors and binding-posts required by mounting a plurality of the contactors on a single frame of conducting material and so connecting the said frame in the motor-circuit that it takes the place of said common conductor.

In Fig. 1 I have shown the contactors T', T', R', R', and R' mounted on a single frame, each having one of its contacts connected electrically to said frame. I have also mounted the contactors R' R' R' R' R' on a single frame of conducting material and connected one of the contacts of each of said contactors electrically to said frame. As shown, the frame of the first group is electrically connected, by means of the conductor 3, with the frame of the second group. It will be understood that the contactors just referred to might all be mounted on a single frame; but for convenience in arrangement and in the assembling of parts the two groups of contactors have been mounted on separate frames electrically connected together. As an illustration of the course of the current through the motor-circuits with this improved contactor arrangement I will trace the circuit through the motors when one of the master-controllers M is in its final series position. In said position all the contactors except R' and P P, which are used only in the parallel positions of the controller, are operated, and the motor-circuit is completed from the trolley T as follows: through conductor 1, conductor 2, switches of the contactors T' T' in parallel through the frame b and frame b', switches of all the resistance-contactors except R' in parallel, the contactors R' R', constituting practically a short circuit for said resistance-contactors through the frames b and b' and conductor 3, thence through conductor 4, motor M', conductor 5, switch of the contactor S, frame b', conductor 6, and motor M' to ground at G.

Referring now to Figs. 2 and 3, A represents the actuating-coil of the contactor, the said actuating-coil being mounted on the frame b and held in place on said frame by means of the cap-plate d. Said base and cap plate are firmly held in the proper position relative to

each other by means of the rods g. The entire structure is adapted to be suspended from the floor of a car or supported in any other desired position, and when fastened directly to the said floor it is held by means of bolts which pass through the openings d' in the cap-plate d. Depending from the said cap-plate d is a fixed core f, which extends into the actuating-coil A. Mounted to reciprocate within said coil A is a movable core g', which is separated from the windings of the said coil by means of the non-magnetic sleeve h and from the fixed core f by means of the non-magnetic disk h'. Pivotally mounted on the lower end of the said movable core g' is the arm k, carrying the contact-terminal k'. Also pivoted at k' is a lever-arm m, which is pivotally mounted on the lug n, carried by the base-plate of the frame b at n', and is electrically connected to said base through the flexible conductor p and the said lug n.

Fastened to the front of each contactor is a plate q, of insulating material, upon which is mounted the fixed contact k'', with which the contact k', carried by the arm k, is adapted to engage. Also carried by the said insulating-plate q is the coil t of the blow-out magnet, the poles t' of which are formed of strips of magnetic material embedded in the side walls q' of the protecting-housing for the contactor-terminals. The said poles t' are adapted to embrace the contact-terminals k' and k'' and are bolted at t' to the core t'' of the blow-out magnet. The roof of the protecting-housing is represented at q''. Mounted within the said protecting-housing are the plates q''' and q'', set at an angle to each other and forming with the side walls of said protecting-housing a flaring blow-out chute. The rods v assist in holding the plates q''' in their proper position. Also mounted within the protecting-housing is a terminal or binding-post o, to which one of the motor-leads which enters the protecting-housing through the opening o' is connected. The other motor-lead is connected to the binding-post o', which is fastened to the frame b and electrically connected therewith. Also mounted within the protecting-housing are the replaceable plates y, of soapstone or other insulating material not readily affected by the arc formed between the contact-terminals k' and k''. These plates may readily be replaced when damaged without the necessity of discarding the entire protecting-housing.

The electrical circuit through the switch and blow-out magnet is shown clearly in Fig. 4 and is as follows: from the binding-post or terminal o through the coil of the blow-out magnet-coil t, fixed contact k'', movable contact k' of the switch, through the arm k, lever-arm m, flexible conductor p, lug n, frame b to the terminal o'.

By constructing the blow-out chute and magnets as above described the arc formed between the contacts of the switch is constrained

to move outwardly away from the actuating mechanism and is gradually lengthened, due to the inclined position of the plates q^3 and q^4 , until disrupted. The coil of the blow-out magnet in addition to the protection afforded by the housing is protected from injury from the arc by the upper inclined plate q^3 .

What I claim as new, and desire to secure by Letters Patent of the United States, is—

- 5 1. In a motor-control system, a motor-circuit, a plurality of separately-actuated contacts forming part of the controller for the motor or motors in said circuit, and electromagnetic means for operating said contacts, the said contacts being mounted upon a single frame forming part of the motor-circuit and also part of the magnetic circuit of said electromagnetic means for operating said contacts.
- 10 2. In combination, a frame of conducting material, and a plurality of switches mounted on said frame each of said switches having one of its contacts electrically connected to said frame, and the contact with which said contact engages supported by said frame but insulated therefrom.
- 15 3. In combination, a frame of conducting material, and a plurality of switches mounted on said frame each of said switches having a contact-carrying arm mounted directly on said frame and a relatively fixed contact supported by said frame but insulated therefrom.
- 20 4. In combination, a frame of conducting material, and a plurality of separately-actuated switches mounted thereon each of said switches having one of its members carried by a movable arm electrically connected to said frame and another member with which said first-mentioned member engages supported by said frame but insulated therefrom.
- 25 5. In combination, a frame of conducting material, and a plurality of separately-actuated switches mounted thereon each of said switches having its movable member mounted on an arm pivoted directly to said frame so that the frame constitutes a common electrical connection for the said movable switch members.

6. In combination, a plurality of electro-magnetically-actuated switches, a frame of 50 conducting material on which said switches are mounted, and means for holding the actuating-coils of said switches in position on said frame said switches being so constructed and arranged that one of the contacts of 55 each switch is electrically connected to said frame.

7. In combination with an electromagnetically-actuated switch, a blow-out magnet whose poles are adapted to embrace the contacts of 60 said switch, a protecting-housing for the contacts of said switch and the coil of said blow-out magnet, and a flaring blow-out chute formed by the side walls of said housing and inclined insulating-plates located within said 65 housing.

8. In combination with a switch, a protecting-housing of insulating material within which the contacts of said switch operate, a blow-out magnet having its coil mounted 70 within the housing and its poles embedded in the side walls of said housing said poles being adapted to embrace the contacts of said switch, and inclined plates mounted within said housing adapted to form with the side 75 walls of said housing a flaring blow-out chute.

9. In combination, in an electromagnetically-actuated switch, a supporting-frame, a solenoid-winding mounted thereon, a switch-contact rigidly mounted at one side of said 80 frame and insulated therefrom, a relatively movable switch-contact carried by an arm pivoted to the supporting-frame, a solenoid-core operatively connected to said pivoted arm, a blow-out magnet adjacent to the switch-contacts, and a flaring blow-out chute formed by side walls and inclined insulating-plates 85 mounted on the side of the supporting-frame and inclosing the switch-contacts.

In witness whereof I have hereunto set my 90 hand this 18th day of February, 1903.

WILLIAM O. MUNDY.
